UNITED STATES PATENT OFFICE.

JOSEPH L. YURACHEK, OF RICHMOND, VIRGINIA.

MAGAZINE HOLDER.

Application filed March 12, 1927. Serial No. 174,865.

This invention relates to magazine holders and has for a particular object thereof the provision of a device for holding magazines in an open position and supporting the magazine, so that it may be conveniently read.

A further object of the invention is to produce a device of this character embodying holding elements which are readily shiftable from place to place, so that they will not interfere with the reading of the magazine.

A still further object of the invention is to produce a device of this character which may be readily and cheaply constructed and which will be durable and efficient in service.

A further object of the invention is to provide a device of this character which may be stored within a small space when not in use.

These and other objects I attain by the construction shown in the accompanying drawings, wherein for the purpose of illustration is shown a preferred embodiment of my invention and wherein:

Figure 1 is a front elevation of a magazine holder constructed in accordance with my invention;

Figure 2 is a side elevation thereof;

Figure 3 is a vertical sectional view thereof;

Figure 4 is a fragmentary transverse sectional view through the frame;

Figure 5 is a detail view of the slides of the ledge;

Figure 6 is a similar view of the slides of the frame;

Figure 7 is an enlarged sectional view on the line 7—7 of Figure 1.

Referring now more particularly to the drawings, the numeral 10 generally designates a substantially rectangular frame having at its lower end a horizontally extending ledge 11. Vertically slidable upon this frame are arms, generally designated at 12, which are adapted to engage over the upper edges of an open magazine at the center of adjacent the edge of the pages thereof.

Longitudinally slidable upon the ledge 11 are vertically extending arms 13, which are adapted to engage the magazine at their approximate center of the leaves thereof and prevent these leaves from bulging outwardly from the forward face of the frame 10 for too great a distance. The frame 10 is

preferably formed from relatively heavy wire, and the frame is braced at its approximate center by a transversely extending brace member 15, which forms a stop, limiting downward movement of the arms 12, as hereinafter more fully set forth.

The upper and lower members of the frame are connected by vertically extending guide wires 16, which form guides upon which the arms 12 are slidably mounted. The guide wires 16 are arranged in pairs, one pair being at the center of the frame and the other pairs being arranged adjacent each side thereof. Each side member 17 has its lower ends extended below the lower end of the frame and formed with an eye 18 providing a means for attaching the frame 10 to a support hereinafter more fully described.

The ledge 11 is preferably likewise formed from wire and comprises an outer member 19, the ends of which are angularly bent and secured to the side members 17 of the frame, as indicated at 20. Connecting the angularly bent portions of the outer member of the ledge 19 is a second wire element 21 paralleling the outer element 19. Adjacent their centers and at opposite sides thereof, braces 22 connect the members 19 and 21 with the lower member 23 of the frame 10 and these braces provide means limiting sliding movement of the arms 13 which are mounted upon the members 19 and 21 toward the center of the completed holder.

Each arm 12 comprises a wire element, bent in U-form and having attached to one arm thereof transversely extending wires 24, the ends of which are formed with eyes 25 slidably receiving the vertically extending wires 16. The cross wires 24 are vertically spaced upon the arm of the U upon which they are attached and are rigidly secured thereto. The arms 13 each comprise a piece 100 of wire bent in L-form, the wire at the end of the foot of the L being reverted, as at 26, so that this revert may overlie the member 21. Secured to the stem 27 of the L is a cross wire 28, the ends of which are 105 downbent and provided with eyes 29 slidably receiving the outer member 19 of the ledge. It will be obvious that the arms 13 will be securely held against oscillatory movements and will, at the same time, be 110 freely slidable upon the members 19 and 21.

The support, at present illustrated, com-

prises a pair of inverted U-shaped leg sections 30. Each arm 31 of each leg section has a projecting extension 32 at that end which joins the cross bar 33 of the U and this projecting extension at its free end is formed with an eye 34. The cross bars 33 are connected by a flexible element 35 limiting their separation.

The eyes 18 of the frame 10 are squared 10 and receive the shoulders 36 of stove bolts 37, the shanks 38 of which are directed through the eyes 34 of the extensions 32 of the leg structure. It will be obvious that by the use of wing nuts 39 upon the shanks of 15 the stove bolts, the frame 10 may be secured in any desired position with relation to the leg structure and the elements of the leg structure may be separated to any desired extent within the limits set by the 20 flexible element 35.

While the device is primarily intended for use with magazines, it will, of course, be understood that it may be employed for holding books, papers, newspapers or the like. 25 It will likewise be understood that while wire is preferred in the construction, any suitable material may be employed therefor.

While the particular method of producing the magazine holder has been suggested, it 30 will, of course, be obvious that the construction herein described is capable of a certain range of change and modification without materially departing from the spirit of the invention and I accordingly do not limit 35 myself to such specific structure except as hereinafter claimed.

I claim:—

1. A magazine holder comprising a substantially rectangular frame having a ledge 40 along one edge thereof, a pair of arms ex-

tending upwardly from the ledge in opposition to the frame and having connection with the ledge whereby they are adjustable longitudinally thereof, other arms opposing the frame and adjustable thereon toward 45 and away from said ledge, said frame structure having extensions provided with eyes and leg structures likewise affording extensions provided with eyes and coacting with the eyes of the frame to receive clamping 50 pivots, whereby the frame may be secured in a desired adjusted angular relation to the leg structure, said leg structure being formed in two sections each of which includes an eye for each eye of the frame structure whereby 55 the sections of the leg structure may likewise be adjusted to the desired angular relation with relation to one another.

2. A magazine holder comprising a substantially rectangular frame having a ledge 60 along one edge thereof, a pair of arms extending upwardly from the ledge in opposition to the frame and having connection with the ledge whereby they are adjustable longitudinally thereof, other arms opposing 65 the frame and adjustable thereon toward and away from said ledge, said ledge including parallel guide wires, said arm at its lower end operating adjacent the outer face of one of said guide wires and having 70 an extension underlying the guide wires and provided at its end with a revert overlying the guide wire remote from that adjacent which it operates and a cross arm on said arm having at its ends eyes engaging the 75 guide wire adjacent which the arm operates.

In testimony whereof I hereunto affix my signature.

JOSEPH L. YURACHEK.
